US00D333505S

United States Patent [19]
Matsumura

[11] **Patent Number:** Des. 333,505
[45] **Date of Patent:** ** Feb. 23, 1993

[54] **APPARATUS FOR PRODUCING
ELECTROLYZED WATER**

[76] Inventor: **Yoshio Matsumura, 45-17, Koie
5-chome, Nishi-ku, Hiroshima-shi,
Hiroshima-ken, Japan**

[**] Term: **14 Years**

[21] Appl. No.: **569,166**

[22] Filed: **Aug. 17, 1990**

[30] **Foreign Application Priority Data**

Feb. 27, 1990 [JP] Japan 2-6280

[57] **CLAIM**

The ornamental design for an apparatus for producing electrolyzed water, as shown and described.

DESCRIPTION

FIG. 1 is a front perspective view of an apparatus for producing electrolyzed water showing my new design;
FIG. 2 is a rear perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a left side elevational view thereof;
FIG. 8 is a right side elevational view thereof; and,
FIG. 9 is a front perspective view thereof, the broken
line drawing being for illustrative purposes only and
forming no part of the claimed design.

FIG.1

FIG.2

FIG. 3**FIG. 4****FIG. 5****FIG. 6****FIG. 7****FIG. 8**FIG. 9
